UNITED STATES PATENT OFFICE.

ELIAS ORAYEH, OF NEW YORK, N. Y.

DESIGN FOR A BELT OR SIMILAR ARTICLE.

SPECIFICATION forming part of Design No. 32,863, dated June 19, 1900.

Application filed May 17, 1900. Serial No. 17,068. Term of patent 7 years.

To all whom it may concern:

Be it known that I, ELIAS ORAYEH, a subject of the Sultan of Turkey, residing in New York in the borough of Richmond, county 5 and State of New York, have invented and produced a new and original Design for a Belt or Similar Article, of which the following is a specification, reference being had to the accompanying drawing, forming part thereof.

10 The drawing gives a perspective view of a belt embodying my new design. The design is, however, adapted for similar ornamental articles.

15 In the drawing, A A are rings in two rows lengthwise of the belt. Through each line of rings is strung a ribbon B. At the ends of the belt a single ring is placed, and the two

ribbons are gathered together to form a single ribbon C at each end. The small rings D D fill in the space between the larger rings A A, 20 as shown.

The leading and material features of my design are the two parallel rows A A, with the two ribbons B B strung along each row, and the small rings D D, as shown in the drawing. 25

Having described my invention, what I claim as new, and desire to secure by Letters Patent, is—

The design for a belt or similar article as herein shown and described.

ELIAS ORAYEH.
